DESIGN FOR A CARD TABLE TOP

Ernest Verity, Freeport, N. Y.

Application July 11, 1933. Serial No. 48,685

Term of patent 14 years

To all whom it may concern:

Be it known that I, ERNEST VERITY, a citizen of the United States, residing at Freeport, in the county of Nassau and State of New York, have invented a new, original, and ornamental Design for a Card Table Top, of which the following is a specification, reference being had to the accompanying drawing, forming part thereof.

The figure is a plan view of the card table top, showing my new design. The card table top is of conventional thickness.

I claim:

The ornamental design for a card table top, as shown and described.

ERNEST VERITY.
